UNITED STATES PATENT OFFICE.

EDWARD W. GRIEVES, OF BALTIMORE, MARYLAND.

BOLSTER-GUIDE PLATE FOR CAR-TRUCKS.

SPECIFICATION forming part of Letters Patent No. 434,336, dated August 12, 1890.

Application filed October 28, 1889. Serial No. 328,401. (No model.)

To all whom it may concern:

Be it known that I, EDWARD W. GRIEVES, a citizen of the United States, and a resident of Baltimore, Maryland, have invented certain Improvements in Bolster-Guide Bars and Guide-Bar Plates for Railroad-Car Trucks, of which the following is a specification.

The object of my invention is to so construct the bolster-guide bar and bolster-guide-bar plate of a railway-car truck that while possessing the necessary strength they will be much lighter than the corresponding parts as now constructed. This object I attain in the manner hereinafter set forth, reference being had to the accompanying drawings, in which—

Figure 1 is a sectional view, partly in elevation, of sufficient of a car-truck to illustrate my invention. Fig. 2 is an enlarged sectional plan view on the line 1 2, Fig. 1. Figs. 3 and 4 are detached perspective views of the main elements of my improved bolster-guide bar, and Fig. 5 is a perspective view of the improved bolster-guide-bar plate.

In Fig. 1, A represents the spring-plank; B, the bolster; and D, D', and D² the various bars connecting the axle-boxes E of the truck and constituting what is ordinarily known as the "diamond" frame of the truck.

The bolster is mounted upon springs supported upon the spring-plank, as usual, and at each end of the spring-plank and bolster, in front and rear of the same, is a bolster-guide bar F, which extends from the lower bar D' of the diamond frame to the upper bar D² of the same, the bolster having both at front and rear a plate G, with ribs or flanges overlapping the bar F, so that the bolster is properly guided in its vertical movements as the springs are contracted and permitted to expand.

Usually the bolster-guide bar and the guide-plate are made of cast-iron, and must necessarily be exceedingly heavy in order to withstand the strains to which they are subjected.

In carrying out my invention I materially decrease the weight of the bolster-guide bar and plate without any sacrifice of strength of the same; in fact, there may in many cases be a material increase in the strength of each of these parts. For this purpose both the guide-bar and the guide-bar plate are composed of

sheet metal struck up into proper form. Thus, as shown in Figs. 2, 3, and 4, the guide-bar consists of inner and outer plates a and b, each corrugated in its central portion, the corrugation of the outer plate b being somewhat deeper than that of the inner plate a, so as to provide between the two plates a central vertical chamber for the reception of the stem of the bolt H, whereby the guide-bar is secured to the upper and lower bars of the diamond frame. Each of the plates also has at its lower end laterally-extending wings d, provided with openings e for the reception of bolts, whereby they are secured to the spring-plank A. Each of the plates also has at the edge a projecting flange f, that of the inner plate overlapping the flange of the outer plate, as shown in Fig. 2, and the two flanges being, if desired, riveted or otherwise secured together, so as to render the bar perfectly rigid and prevent any accidental springing or separation of the plates composing the bar. The inner plate has at top and bottom a projecting flange g, these flanges forming bearings for the top and bottom bars of the diamond frame, and being provided at their opposite edges with ribs i for engaging with said bars and aiding in the maintenance of the guide-bar in proper position in respect to the frame. The flanges g bear upon and are braced and stiffened by the outer plate b, the corrugation of which extends almost to the outer edges of the flanges. The inner plate a may, if desired, be furnished with a lateral extension a', provided at its upper end with projecting ears m for the reception of a portion of the brake-gear; but this extension is immaterial and may be omitted in many cases.

The guide-bar plate G has hollow ears or projections n, formed by striking up the plate in suitable dies, these ears or projections overlapping the flanged edges of the guide-bar and serving to insure the proper vertical movement of the bolster. Laterally beyond the ears n the guide-bar plate is provided with wings p, which are bolted to the bolster, and in order to aid these bolts in retaining the guide-bar plate in proper longitudinal position on the bolster that portion of the plate between the ears n is sunken in respect to the wings p, so that it enters a recess formed in

the side of the bolster, as shown in Fig. 2, the opposite shoulders *x* thereby formed serving to prevent movement of the guide-bar plate on the bolster in either direction.

5 Although in carrying out my invention I prefer in constructing the bolster-guide bar to use both the inner and outer plates, as shown, either of these plates separately might be sufficient in some cases.

10 Having thus described my invention, I claim and desire to secure by Letters Patent—

1. The within-described bolster-guide bar for railroad-car trucks, the same consisting of a sheet-metal plate struck up to form ribs or corrugations, whereby the desired structural strength is imparted thereto, substantially as specified.

2. The within-described bolster-guide bar for railroad-car trucks, the same consisting of a corrugated sheet-metal plate with opposite edge flanges, substantially as specified.

3. The within-described bolster-guide bar for railroad-car trucks, the same consisting of two plates of sheet metal secured together and forming between them a chamber for the reception of the bolt, whereby the bar is secured to the truck-frame, substantially as specified.

30 4. The within-described bolster-guide bar for railroad-car trucks, the same consisting of two plates of sheet metal located face to face and each having edge flanges, those of one plate being confined to those of the other plate, substantially as specified.

35 5. The within-described bolster-guide bar for railroad-car trucks, the same consisting of two corrugated plates of sheet metal secured together, the inner plate having at top and

bottom projecting flanges overlapping the 40 corrugations of the outer plate and forming bearings for the top and bottom bars of the truck-frame, substantially as specified.

6. The within-described bolster-guide bar for railroad-car trucks, the same consisting of 45 a pair of sheet-metal plates located face to face, and each having at the lower end laterally-projecting ears whereby they are secured together and to the spring-plank, substantially as specified.

50 7. The within-described bolster-guide bar for railroad-car trucks, the same consisting of a sheet-metal plate having at one side a wing or extension, with projecting lugs for the reception of part of the brake-gear, substantially as specified.

55 8. The within-described bolster-guide bar plate for railroad-car trucks, the same consisting of a plate of sheet metal having hollow ribs or ears struck up therefrom for engagement with the guide-bar, substantially as specified.

60 9. The within-described bolster-guide bar plate for railroad-car trucks, the same consisting of a plate of sheet metal having opposite hollow guide lugs or ears struck up therefrom and securing-wings beyond said guide-lugs, that portion of the plate between the lugs being deeper than the wings beyond the lugs, so as to enter a recess in the bolster, substantially as specified.

65 In testimony whereof I have signed my name to this specification in the presence of two subscribing witnesses.

EDWARD W. GRIEVES.
